(57) **CLAIM**

The ornamental design for a dental instrument, as shown and
described.

DESCRIPTION

FIG. 1 is a perspective view of a dental instrument showing
our new design;

FIG. 2 is a left side view thereof which is a mirror image to
the right side view;

FIG. 3 is a top view thereof; and,
FIG. 4 is a front view thereof.

The broken lines shown in the figures represent portions of
the dental instrument that form no part of the claimed
design.
